UNITED STATES PATENT OFFICE.

JAMES S. CRAIN, OF EL PASO, TEXAS.

CALCULATOR.

Application filed September 12, 1922. Serial No. 587,775.

To all whom it may concern:

Be it known that I, JAMES S. CRAIN, a citizen of the United States, residing at El Paso, in the county of El Paso and State of 5 Texas, have invented new and useful Improvements in Calculators, of which the following is a specification.

This invention relates to improvements in calculators, and the general object of the 10 invention is to provide a simple, convenient and readily understood type of calculator by means of which instantaneous results in the solving of certain problems may be secured, without the necessity of lengthy and 15 involved figuring.

Specifically stated, the object of the invention is to provide a ready calculator for the use of merchants or others whereby may be accurately and instantly calculated, first, 20 the amount at which articles bought at a certain price per dozen should be sold in order to realize a certain percentage of profit based on the selling price; second, the cost per article of any certain number of 25 articles bought at a certain price per dozen, enabling the unit cost price to be obtained for inventory or other purposes; and, third, an arrangement whereby, for convenience in marking goods, the cost and selling prices 30 may be obtained as well as profit percentage, all in a readily apparent manner.

The invention consists of the features of construction, combination and arrangement of parts, hereinafter fully described and 35 claimed, reference being had to the accompanying drawings, in which:—

Figure 1 is a side elevation of a form of calculator embodying my invention.

Figure 2 is a view of one of the indicating blades or rules.

Figure 3 is a vertical section through one end of the calculator.

Figure 4 is an end elevation of the calculator.

Figure 5 is a view of the indicating blade or rule illustrated in Figure 2, showing more fully the indicia thereon.

Figure 6 is a plan view of the indicator sheet bearing the calculating tables out-spread.

Figure 7 is a view of the other indicating blade or rule.

In the form of my invention herein disclosed, I provide a supporting frame comprising upright end pieces 1 connected by

one or more base or bottom pieces 2 and also by longitudinal side pieces 3 and 4, which side pieces 3 and 4 serve also as fixed indicating members, as hereinafter described. Supported by the frame is a rotary drum or cylinder 5 provided at each end with a journal 6 terminating in an actuating knob or handle 7. The journals 6 pass through and turn in openings 8 in the end pieces 1 whereby the drum or cylinder 5 is mounted to revolve.

On the periphery of the drum or cylinder are two charts or tables 9 and 10, the chart or table 9 being continuous, while the chart or table 10 is, for convenience, divided into 70 two sections 11 and 12, to adapt the indicia thereon to be properly disposed and arranged within the described space allowed. The chart or table 9 is movable by rotating the drum or cylinder with relation to 75 the cooperating fixed indicator 3, while the chart or table 10 is movable by rotating the drum or cylinder for cooperation with the fixed indicator 4.

The indicating member 3 is in the form 80 of a rule or blade bearing thereon a transverse space 13 containing the heading "No. of units", and also bearing thereon a longitudinal space 14 sub-divided by transverse lines into column heading spaces bearing 85 certain numerals, as shown, representing prices per dozen in various amounts from 15¢ to \$5.00. The rule also preferably bears certain directions, hereinafter referred to, in explanation of how it should be used, as an 90 example, in connection with the table or chart 9 for making calculations.

The table or chart 9 extends approximately along and around one half the circumference of the drum or cylinder 5 and is provided with ruled lines forming longitudinal and transverse (circumferential) columns. At one end of the chart is a transverse column 15 bearing the numerals from 1 to 23, inclusive, representing units, and these units are arranged in parallel relation to and aligned with other columns 16 arranged both longitudinally and circumferentially to cooperate respectively with the fixed indicator 3 and the numerals of column 15. 100 The said columns 16 contain numerals, expressed in whole numbers and decimals or otherwise, representing units cost figures, based upon the cost price per dozen, expressed by the figures in the head columns 105 110

14, of articles the number of which are expressed by the numerals in the column 15. A first left-hand transverse column, for example, cooperates with the first head space 5 containing the figure .15 of indicator 3 and contains figures, arranged in the spaces thereof opposite the numerals in column 15, expressing the cost price, at the rate 15¢ a dozen, of any certain number of articles expressed by a numeral in the column 15 lying opposite the adjacent numeral in the said first column 16. Thus, for example, the cost price of four articles or units, as expressed by numeral 4 in column 15, at the 10 rate of 15¢ per dozen is given by the figure .05, lying opposite the numeral 4 in the first column 16.

The fixed and movable indicators 3 and 9 are provided to enable a merchant to instantaneously calculate the value of any certain number of units or articles bought at the rate of a certain sum per dozen. On the face of the indicating blade 3 appears explanatory directions indicating the mode of use 20 of the indicators for such purpose. According to this, it will be seen that if it should be desired to ascertain the value of seventeen articles which cost \$2.25 per dozen, the cylinder is turned until the numeral 25 17 in column 9 is brought into registry with an edge of the blade 3 opposite column 13, and then by reference to the figure in the sub-division of that column 16 registering with \$2.25 of scale 14, and which alines 30 transversely with column numeral 17, it will be found that the correct value of the seventeen units or articles is expressed by the figures 3.18 $\frac{1}{4}$, or \$3.19. In this manner the value of any certain number of articles costing 35 at the rate of so much per dozen, as expressed by the figures in the column 14 of indicator 3, may be instantly and accurately determined, and, of course, it will be understood that the cost per dozen figures 40 45 and the figures on the chart 9 may be calculated to express the value of any number of articles at any range of cost per dozen prices which may be suited to any particular kind of business.

50 The chart 10 occupies the other half of the circumference of the drum or cylinder and the chart section 12 constitutes a continuation or prolongation of the chart section 11, the chart 10 being thus arranged in sections 55 in order that the available space may be utilized to the best advantage, so that a drum or cylinder of excessive size will not be required. The chart sections 11 and 12 are sub-divided by vertical and transverse 60 lines into longitudinal and transverse columns and spaces. In the spaces at the top of the chart section 11 are numerals, 65 decimal expressed, to represent cost prices per dozen, the range being from .10 to .65, while in the spaces across the top of chart section

12 are similar figures carrying the cost per dozen price range from .70 to \$3.25. Below the numerals in the chart sections 10 appear 70 decimal expressed rows of numerals which fall in columns under the head spaces containing the price per dozen figures, and which also are arranged in transverse alignment so as to form transverse columns.

The fixed scale or indicator 4, like the indicator 3, comprises a blade or rule, and this 75 blade or rule is adapted for cooperation with the chart sections 11 and 12. The face of the blade 4 is provided with two scales for cooperation respectively with the chart sections 11 and 12. The scales are alike in 80 character, each containing numerals in multiples of five from 5 to 50, which are arranged to aline with transverse rows of decimal 85 expressed numerals in the chart section opposite which the scale appears. Above each scale appears a head space containing the words "Cost per doz." which registers with the transverse row of cost per dozen numerals in the opposite chart section, and between said head space and 90 the scale is an indicating heading for the scale consisting of the words "Cost per unit." The head row of transverse numerals of the chart sections represent, as stated, cost per dozen figures, and the numerals in the horizontal and transverse rows of the chart sections represent sums at which units or articles, costing so much per dozen, should be sold in order to realize certain percentages 95 of profit expressed by the numerals on the fixed indicator scale. The indicator 4 bears directions explanatory of the mode of use of this part of the device. Thus supposing an article costing \$3.50 per dozen is to be sold at a profit of 25%. To calculate the 100 price at which the article is to be sold, the cylinder is turned until the proper cost per dozen figure in the head column of chart section 11 or chart section 12, chart section 11 in the present instance, registers with the 105 proper percentage numeral on the indicator 4, from which it will be seen that the amount at which the article should be sold is expressed by the figures .0389. In this 110 example the numeral 35 is advanced a decimal point and mentally read at \$3.50, and the resultant .0389 will be advanced similarly a decimal point so as to read .389, or 39¢. While the cost per dozen numerals are, 115 for convenience, expressed in a certain way, it is to be understood that these numerals, and similarly the numerals giving the results in the underlying columns, may be 120 decimal shifted one or more points forwardly or backwardly so as to vary their calculating ratio accordingly, which may be 125 very conveniently carried out by the operator, allowing the range of calculation to be extended to a large degree without using long tables. In the manner described the 130

merchant may easily and quickly figure the exact amount at which any article, costing so much per dozen, should be sold in order to realize a certain percentage of profit.

- 5 One of the percentage scales of the indicator 4 is shown as provided with indicating characters, in the form of the alphabetical letters from A to J, inclusive, arranged opposite the percentage numerals therein.
- 10 These letters may be used as code marks for marking profit percentages on the price tickets attached to the articles to be sold, so that the merchant or his assistant can determine at a glance the amount of profit
- 15 which will be realized from the sale over the sale price given thereon. These code letters may be used with the resultant calculating figure of the proper chart section to enable the merchant to mark his
- 20 price tickets so that they will give at a glance first the selling price of the article and then confidentially the cost price per dozen of the article and the marked percentage of the profit. Thus, for instance,
- 25 if the merchant wishes to sell shirts costing \$8.50 per dozen at a profit of 45%, he can determine by reference to the scale under .85 that the unit selling price is given at .1287, indicating that the shirts should be
- 30 sold at the rate of \$1.28 each. By placing this sale or retail price on the sales ticket, followed by the figure .85 and code letter B, the merchant can read at a glance the facts as stated, that the shirts cost him
- 35 \$8.50 per dozen and that in selling them at \$1.28 each, he is realizing a figured profit of 45%.

From the foregoing description, taken in connection with the drawings, the construction and mode of use of my improved calculator will be readily understood, and it will be seen that the invention provides a device of this character of great convenience and value to merchants in enabling a merchant to instantly determine, for inventory or other purposes, the value of any certain articles of a kind at a cost price per dozen, and also to enable him to determine the prices at which he should sell articles costing so much per dozen in order to realize a certain percentage of profit, enabling goods to be quickly marked, calculations made for reductions at any time when desired or required, and an inventory made

55 without referring to old bills or accounts

and without the loss of time and amount of trouble incident thereto.

Having thus fully described my invention, I claim:

1. A calculator comprising a frame, a fixed indicating member having a transversely disposed units reference column and a longitudinally disposed column of figures subdivided into transverse columns containing the various figures, and a movable indicating member bearing a chart having a transversely disposed column of figures for cooperation with the units designating column of the fixed indicator and having columns of figures subdivided into longitudinal and transverse rows in registering alinement respectively with the figures in the units column of said movable indicating member and with the figures in the subdivisions of the longitudinal column of the fixed indicating member.

2. A calculator comprising a frame, a fixed indicating member at one side of the frame having a transversely disposed units designating column and a longitudinally disposed column of figures subdivided into transverse spaces separating said figures from each other, a fixed indicating member at the opposite side of the frame having separate columns of similar character provided with transversely disposed figures therein, and a movable indicating member having a main chart for cooperation with the first-named fixed indicator and provided with a transverse column bearing units designations and columns of figures subdivided into longitudinal and transverse rows for cooperation with the units figures and the figures in the subdivided column of said first-named fixed scale, and a pair of transversely disposed charts for cooperation with the respective columns of the second-named fixed indicator, said charts having transversely arranged head spaces containing figures of progressively increasing values and columns of figures subdivided into longitudinal and transverse rows for cooperation with said figures in the head columns and with the figures of the respective scales on the second-named fixed indicator.

In testimony whereof I affix my signature.

JAMES S. CRAIN.
